MULTISTORY BUILDING

Esa M. Khoury, 20401 Napa St., Canoga Park, Calif.

Filed Oct. 3, 1957, Ser. No. 687,939

7 Claims. (Cl. 20—1.13)

This invention has to do with multistory buildings embodying ramp means whereby motor vehicles can be driven from one floor to another and particularly to buildings of this nature which are used for the parking of vehicles.

An object of the invention is to provide a simple, novel, improved and easily constructed multistory or multideck building particularly suitable for use as a garage for storage or parking of automobiles.

Another object is to provide a building structure wherein a pair of complementary sections of each floor are inclined or warped in a novel manner to provide unique ramp means from floor to floor.

A further object is to provide a multistory building embodying a novel warped floor or deck construction which in one form enables the floor levels on at least three sides of a rectangular building, and in another form on all four sides of such a building, to be kept level thereby providing a building with horizontal exterior lines.

In recent years, there appears to be a trend toward tall office and hotel buildings with parking floors or decks associated with the buildings both above and below the surface of the ground, with the office or hotel portion of the structure projecting up from the center of the parking area. Where such is the case, horizontal lines become very important on all four sides, particularly where an entire city block or other large rectangular area is involved. It is a particular object of my invention to provide a warped deck type of structure which permits the architect to include the garage as a part of the building with horizontal exterior lines and without unsightly ramps or separate spiral ramps which take up much parking area. It is a further object to provide a warped deck or floor construction which may be confined to the interior of the building and thereby permit drive and parking space around a level perimeter area of each floor. The horizontal exterior lines attained by such a building are a desirable feature in the design of city-block parking structures, permitting this type of structure to fit into the surrounding architecture. The level perimeter area of each floor of the structure outwardly of the warped area may be used either for office space or for vehicle storage, and thus the perimeter area, being level, will blend in with the rest of the building irrespective of the use to which it is put.

A further object is to provide a warped deck construction in the form of a hyperbolic paraboloid, which, although it may appear difficult to build, is actually simple since it can be laid out with straight lines extending in two directions, as will later appear. Once one deck or floor is constructed in place, succeeding decks or floors are exactly one story height apart in elevation at any point. This being the case, all the shoring needed for a concrete floor can be cut the same height and used for the entire area. Also, since my warped deck can be designed and constructed with straight lines, it can be readily constructed with steel

2

as well as concrete, or with a combination of both steel and concrete, or any other structural floor material can be adapted to it. Another advantage of my warped construction is that it is built as an integral part of the floor. Thus, there is a saving in construction cost since the entire floor, including the ramp means in the form of warped sections, can be constructed at one time. In ordinary types of building, the ramps are separately constructed apart from the floors.

Another object is to provide a novel structure designed for a parking garage to occupy an entire city block or other large rectangular area and embodying warped floor sections which provide two main regions for the travel of motor vehicles from floor to floor, thereby enabling the use of one region for the travel of cars upwardly, and the other, for the travel of cars downwardly. Another object is to provide a construction which makes for minimum slope or grade, and one which provides for the parking or storage of vehicles within the area of travel of the vehicles in ascending or descending.

A still further object is to provide a warped floor section, or deck multistory garage building which has certain advantages in resisting lateral loads. In this connection, it is an object to provide a construction embodying a pair of sections which are separated at their inner edges and may be separated by any desired amount provide access means for pedestrians such as elevators, escalators or steps.

These and other objects will be apparent from the drawings and the following description. Referring to the drawings:

Fig. 1 is a perspective view of a building embodying the invention;

Fig. 2 is a plan view of the upper floor of the building, partially broken away;

Figs. 3 and 4 are sectional views on lines 3—3 and 4—4, respectively, of Fig. 2;

Fig. 5 is a fragmentary perspective view of a modified form of the invention;

Fig. 6 is a plan view of the upper floor of the structure shown in Fig. 5;

Fig. 7 is a sectional view on lines 7—7 of Fig. 6; and,

Fig. 8 is a diagrammatic view of a typical warped section.

More particularly describing the invention, referring first to Figs. 1—4, I show in Fig. 1 several floors or decks 11 of a rectangular multistory building as they appear in perspective. The floors may be supported in vertically spaced relation upon suitable columns 12 or in any other conventional manner. Each floor comprises an outer marginal level section or area, this being designated 15 along one side of the building and designated 15' at each end thereof. These level sections 15 and 15' are all at the same elevation for each floor and are connected to the floors above and below by an inclined floor area or section 17 which runs along the other side of the building. The inclined area 17 may be arbitrarily divided into two parts 17a and 17b, with the part 17a of one floor being connected to and forming a continuation of the part 17b of the next lower floor.

It is a particular feature of my invention that each floor is provided with a pair of aligned sections designated 20A and 20B, which I will term "warped" sections. These sections adjoin the sections 15 and 15' along the margins designated by broken lines 21 and 22. However, the two sections 20A and 20B are oppositely inclined or warped toward the adjacent corners designated 25 and 26, respectively. Thus, section 20A declines toward its corner 25 while section 20B inclines upwardly

to its corner 26. Section 20A slopes straight upwardly along the broken line 28 where it joins the inclined section 17a. Also, its inner edge 29 slopes upwardly in a straight line to section 15.

Each warped floor section 20A and 20B may be described as a hyperbolic paraboloid. While at first impression, this might seem difficult to construct, in reality it is easy, since the section can be constructed throughout with straight lines. This is illustrated in Fig. 8, where, by way of illustration, I show the simplicity of the form involved. Referring to Fig. 8, the four lines 30, 31, 32 and 33 define the boundaries of a rectangular, horizontally disposed plane, the view being drawn in perspective. The lines 30, 31, 34 and 35 indicate the boundaries of a so-called warped section, the lines 34 and 35 converging at the lowest portion or corner of the section, vertically below the intersection of lines 32 and 33. The lines 34 and 35 are straight, inclined lines disposed in planes normal to each other, and in planes common to the lines 32 and 33, respectively. In like manner, any straight line 37 in a plane at right angles to line 30 and intersecting line 34 defines the surface of the warped section along such line. Also, any straight line 38 in a plane at right angles to line 31 and intersecting line 35 defines the surface of the warped section along such line. It will be apparent, of course, that the surface bounded by the lines 30, 31, 34 and 35, although straight along any of lines 37 or 38, or ones parallel thereto, is curved along any line diagonal thereto, the curvature being such that the surface is, in reality, a hyperbolic paraboloid.

Since section 20B is warped oppositely to section 20A, and thus in inclined or warped upwardly to its corner 26, the margin 42 of the section adjoins part 17b of the inclined section 17. Also, since the sections are oppositely inclined they are separated at their inner edges at 29 and 44, respectively, and at this point, they may terminate substantially along a common plane as indicated although they may be spaced apart any desired distance to provide space for elevators, a moving stairway, or conventional stairs. Also stairs, such as those at 45 in Fig. 2, may be formed along the adjacent edges of the sections 20A and 20B, if desired.

With the construction outlined, it will be apparent that each warped section has a maximum vertical deflection or vertical offset of one-half story so that at any corner 25 or 26 the building is midway in elevation between the level sections 15-15' of the floors. Thus, all sections of each floor are spaced one story vertically with reference to corresponding sections of adjacent floors.

Also, my multistory building provides horizontal floor areas along three sides with an inclined floor area along only one side. Further, it will also be apparent, by reference to Fig. 2, that the inclined or warped sections 20A and 20B, in conjunction with the adjacent portion of section 17, provide unique ramp means adjacent the center of the building. Line 48 designates the general path vehicles would follow from floor to floor while the arrows thereon designate the direction of travel for going upwardly from floor to floor. By traveling in a reverse direction vehicles can descend from floor to floor. It should also be apparent that this type of floor construction enables the parking of vehicles around the entire margin or peripheral area of the structure, as in the stalls, designated 53, and that it also provides ample double stall parking area 55 substantially entirely upon the inclined sections of the floor as well as a central parking area 56 on each side of the central separation. Also since the areas 15 and 15' are level on each floor, these are suitable for use as store or office space in lieu of being used as parking area. Other features and advantages of the construction have been pointed out hereinabove.

Referring now to Figs. 5-7, I show another form of

the invention which utilizes the basic structure heretofore shown but in a manner to provide a multistory building having a level floor area completely around or on all four sides of each floor of the building, thereby providing a building which is suitable for construction to extend over an entire city block or other area where the building will be exposed to view on all four sides.

In this form of the invention, the floors of the building, designated 60, are each shown as having a marginal level section completely around the perimeter, designated generally 61 and comprising the sections 61A, 61B, 61C and 61D. The floors are shown supported on columns 63. Centrally of the building, I provide a pair of inclined or sloping sections, designated 64 and 65. Section 64 declines or is inclined downwardly from the level section 61D to the central part of the building, designated by the broken line 66. At the line 66, the elevation is one-half story below the level of area 61. Section 65 is oppositely inclined to the section 64 and thus 20 extends upwardly from the level section 61B so that at its inner edge 68 it is spaced one story above the line 66. It will be apparent that the section 64 of one floor forms a continuation of the section 65 of the next lower floor, although in Fig. 5 I show the uppermost floor with the section 65 terminating at the edge 68.

Alongside the central inclined sections 64 and 65, I provide four so-called "warped" sections, designated 70A and 70B and 71A and 71B. These warped sections are similar to the sections 20A and 20B previously described. 30 The sections 70A and 71A decline toward the corners 73 and 74, respectively, while the sections 70B and 71B slopingly curve upwardly toward the corners 75 and 76, respectively. On one side sections 70A and 70B join with the level section 61A. On the other they join with sections 64 and 65, respectively. In like manner section 35 71A and 71B join the level section 61C along one lateral margin and are joined to the sections 64 and 65, respectively, along their other lateral margins. At their outer ends, sections 70A and 71A are joined to the level section 61D, while sections 70B and 71B are joined at their outer end to level section 61B.

It will be apparent that with the construction provided there are formed two rampway traffic paths in the building which motor vehicles may follow either upwardly or 45 downwardly from floor to floor. In Figs. 5 and 6 the line 80 shows these paths as well as the connecting paths across the central sections 64 and 65. The arrows arbitrarily designate an ascending route in the region of floor sections 71A and 71B and a descending path in the region 50 of sections 70A and 70B. Obviously vehicles may be driven in the opposite of these directions in each of the areas, if desired. However, by using one area for ascending traffic and the other for descending traffic, there is much less chance of collision taking place.

In Fig. 6 I have shown the perimeter parking area divided into appropriate parking stalls 82. I also show various parking stall areas as designated by the numeral 83 as well as central parking area stalls 84. Arrows 86 show the paths to be followed by vehicles to and from the parking stalls.

As previously indicated, the outer portion of any floor 65 may be used for office or store space rather than being devoted to the parking of automobiles where this may be desirable. It will be apparent that the construction shown in Figs. 5-7 retains all the advantages of the previously described structure but, at the same time, provides a building having level, horizontal floor areas on all four sides with the various advantages thereof previously described.

It is to be understood that, although I have shown and described preferred forms of my invention, I contemplate that various changes and modifications can be made therein without departing from the scope of the invention as indicated by the claims which follow.

I claim:

1. In a multistory building suitable for use as a garage, a plurality of floors in superposed relation, each floor including a pair of rectangular, oppositely inclined warped sections of hyperbolic paraboloid form and a continuous level section marginal to one side of said warped sections and to each end of said warped sections, and an elongated inclined section marginal to the other side of each said warped sections the inclined section along the other side of each warped section forming a continuation of the inclined section of the next adjacent floor, respectively, said warped sections being separated along their adjacent edges and each being diagonally warped in a direction to produce maximum vertical deflection at an inner corner point adjoining said inclined section and adjacent the inner corner point of maximum vertical deflection of the other warped section.

2. A multistory building as set forth in claim 1 in which said warped sections have a maximum vertical deflection of one-half story and in which the level section of each floor is spaced one story vertically with relation to the level sections of the next adjacent floors.

3. A multistory building as set forth in claim 1 in which the elongated inclined section marginal to said other side of each warped section is level along any line normal to its direction of inclination.

4. In a multistory building having a plurality of superposed floors, ramp means extending from floor to floor, comprising a pair of rectangular warped sections of hyperbolic paraboloid form on each floor and an inclined section along one side of each warped section, the inclined section along the side of the warped section of one floor forming a continuation of the inclined section along the side of a warped section of the next adjacent floor, said warped sections being in alignment with a separation between them and being diagonally oppositely warped toward an inner corner adjacent said inclined section whereby one section is elevated in a direction toward its said corner and the other is depressed downwardly to its said corner.

5. In a multistory building having a plurality of superposed floors, each floor comprising a level outer marginal area on three sides, a pair of aligned inclined areas extending inwardly from the level marginal area at two sides toward each other, one of said inclined areas extending downwardly in a direction toward the other and the other extending upwardly in a direction toward said one whereby said areas are vertically separated at their

inner boundaries, said inclined areas forming continuations of similar areas, respectively, of the adjacent floors whereby a ramp is formed from the level outer marginal area at one side of the building of one floor to the level outer marginal area at the opposite side of the building of the next floor, a pair of separated, aligned warped areas adjoining said inclined areas on one side thereof, said warped areas being warped to meet the adjoining inclined areas and joining at two sides with said outer marginal area.

10 6. The structure as defined in claim 5, in which a second pair of separated, aligned warped areas adjoining said inclined areas on the opposite side thereof, said second pair of warped areas being warped to meet the adjoining inclined areas and joining at two sides with said outer marginal area.

15 7. In a multistory building having a plurality of superposed floors, each floor comprising a level outer marginal area on at least three sides thereof, a pair of aligned inclined areas extending inwardly from the level marginal area at two said sides toward each other, one of said inclined areas extending downwardly and having a boundary in a direction toward the other and the other extending upwardly and having a boundary in a direction toward 20 said one whereby said areas are vertically separated at their inner boundaries, said inclined areas forming continuations of similar areas, respectively, of the adjacent floors whereby a ramp is formed from floor to floor, a pair of aligned warped areas, each substantially of hyperbolic paraboloid form, adjoining said inclined areas on one side thereof, said warped areas being diagonally warped to meet the adjoining inclined areas and joining at two sides with said outer marginal area, and a second pair of aligned warped areas, each substantially 25 of hyperbolic paraboloid form, adjoining said inclined areas on the other side thereof, said warped areas of said second pair being diagonally warped to meet the adjoining inclined areas and joining at two sides with said outer marginal area.
